(57) **CLAIM**

I claim the ornamental design for aircraft overhead cargo system, as shown and described.

DESCRIPTION

FIG. 1 is a perspective view of a container of the aircraft overhead cargo system;

FIG. 2 is a front view of the container;

FIG. 3 is a left side view of the container;

FIG. 4 is a right side view of the container;

FIG. 5 is a rear view of the container;

FIG. 6 is a top view of the container;

FIG. 7 is a bottom view of the container;

FIG. 8 is a bottom perspective view of the container;

FIG. 9 is a top perspective view of the container in an open position;

FIG. 10 is a bottom perspective view of the container in an open position; and,

FIG. 11 is an environmental view of the container.

The design is of indefinite length as shown in the reproduction. The broken lines portion in FIG. 11 shows environmental unclaimed subject matter. The broken lines form no part of the claimed design.
